CLAIM

We claim the ornamental design for an electronic device, as shown and described.

DESCRIPTION

FIG. 1 is a front perspective view of a first embodiment of an electronic device, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a front perspective view of a second embodiment of the electronic device, showing our new design;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof;

FIG. 16 is a rear perspective view thereof;

FIG. 17 is a front perspective view of a third embodiment of the electronic device, showing our new design;

FIG. 18 is a front view thereof;

FIG. 19 is a rear view thereof;

FIG. 20 is a left-side view thereof;

FIG. 21 is a right-side view thereof;

FIG. 22 is a top view thereof;

FIG. 23 is a bottom view thereof;

FIG. 24 is a rear perspective view thereof;

(Continued)

FIG. 25 is a front perspective view of a fourth embodiment of the electronic device, showing our new design; FIG. 26 is a front view thereof; FIG. 27 is a rear view thereof; FIG. 28 is a left-side view thereof; FIG. 29 is a right-side view thereof; FIG. 30 is a top view thereof; FIG. 31 is a bottom view thereof; and, FIG. 32 is a rear perspective view thereof. The broken lines in the figures depict portions of the electronic device that form no part of the claimed design. The dot-dash broken lines in the figures represent a boundary and form no part of the claimed design.
